Primary Examiner — Samantha Wood*Assistant Examiner* — Aula Soroush(74) *Attorney, Agent, or Firm* — FRESH IP PLC; Clifford D. Hyra; Aubrey Y. Chen(57) **CLAIM**

The ornamental design for a pet carrier, as shown and described.

DESCRIPTION

FIG. 1 is a front perspective view of a pet carrier, in a first embodiment;

FIG. 2 is a rear perspective view thereof;

FIG. 3 is a front view thereof;

FIG. 4 is a rear view thereof;

FIG. 5 is a side view thereof;

FIG. 6 is another side view thereof;

FIG. 7 is a top view thereof; and,

FIG. 8 is a bottom view thereof.

The broken lines in the drawings illustrate portions of the pet carrier that form no part of the claimed design.
